UNITED STATES PATENT OFFICE.

TIMOTHY G. PALMER, OF SCHULTZVILLE, NEW YORK.

TORPEDO-SIGNAL FOR RAILWAYS.

SPECIFICATION forming part of Letters Patent No. 285,920, dated October 2, 1883.

Application filed April 2, 1883. (No model.)

To all whom it may concern:

Be it known that I, TIMOTHY G. PALMER, of Schultzville, in the county of Dutchess and State of New York, have invented an Improvement 5 in Torpedo-Signals for Railways, of which the following is a specification.

At drawbridges and sidings it is customary to display a danger-signal for the train to be stopped when the main track is not in a condition for use. This danger-signal is usually a red flag or disk in daytime and a red lantern at night. Many instances have occurred where accidents have taken place or been scarcely avoided by the signal not having been noticed 15 by a careless or sleepy engineer, or one whose attention has been otherwise momentarily attracted. Torpedoes have been placed upon the track in many instances, but they usually require personal handling to put them in place 20 or to remove them.

My present invention is for the purpose of providing an automatic torpedo-signal and combining therewith a visual signal, so that when the ordinary visual danger-signal is displayed 25 a torpedo will be automatically placed in position to be acted upon by the wheels of a passing engine or car and attract the attention of the engineer or conductor by the noise of the explosion.

30 In the drawings, Figure 1 is an elevation illustrating one of the modes in which the visual and detonating signals are combined. Fig. 2 is a cross-section of the torpedo-carrier. Fig. 3 is a longitudinal section, and Fig. 4 a plan of the same.

The ordinary visual signal is usually composed of a post, *a*, with arm or arms *b* and disk *c*, or lantern. The manner of operating this and the character of the signal itself will 40 vary according to the place, and I remark that my improvement may be combined with any visual signal, the signal shown being merely introduced for the purpose of illustration.

It is usual to place the visual signal at sufficient distance from the switch or draw for the train to be stopped after passing that signal; hence I apply to the side of the track, 45 near the visual signal, the automatic torpedo apparatus and operate the two signals simultaneously.

In operating the visual signal it is usual to employ a rod running along the track from

the bridge or switch to the signal-post, and to use levers or a chain passing around a pulley to connect the longitudinal rod with the vertical rod leading to the signal-arms. These parts may be of any desired character. I have shown the vertical rod *d* to the signal-arms as connected to the bent lever *f*, and from this a rod, *e*, passes to the torpedo-slide *g*, so that as 55 the danger-signal is displayed the torpedo-slide *g* is moved up against the side of the track, and as the danger-signal is removed the torpedo-slide is drawn back, the object being to place a torpedo in the path of the wheels while 60 the danger-signal is displayed and to withdraw the same as soon as the danger is over.

I will now proceed to describe the automatic torpedo apparatus itself.

The base *k* is made with a flange, so that it 70 can be spiked upon a cross-tie or base-block, and the end of this base *k* abuts against the outer side of the track-rail *l*. The top of this base is made as a dovetail or ribbed support, 75 upon which the torpedo-slide *g* can be moved back and forth freely. It is preferable that either the top part of the base *k* or the under part of the torpedo-slide be made of brass, so that the parts cannot rust together. The end of the torpedo-slide is made to fit the side of 80 the rail-head, so that the slide, when in the danger position, will be close up against the outer side of the rail. In the torpedo-slide there is a recess in the top surface, close to the end, of a size adapted to contain an ordinary railway-torpedo, so that this torpedo 85 is brought up automatically at the side of the track, and so close to the rail that the tread of the wheels, being wider than the rail, will press upon such torpedo and explode the same and give the detonating railway danger-signal. When the torpedo-slide is drawn back, the torpedo 90 is out of the way and will not be exploded. I employ a cap or hood, that incloses the torpedo-slide and torpedo when drawn back, so that the same is not liable to become 95 misplaced or injured. This hood should be set closely over the parts, and may be removable and provided with a lock to hold it firmly when in place.

If a magazine of torpedoes is used, it is necessary to add to the foregoing devices an automatic mechanism for discharging the spent shell. I have represented a magazine for such

torpedoes at *p*, the same being above the torpedo-slide and forming part of the case that incloses said slide. This magazine is of the size of the torpedo, and provided with a movable cover. When the torpedo is in place, it will be drawn back beneath the pile of torpedoes at each movement that removes the danger-signal, but if the torpedo has been exploded or removed, a fresh torpedo will drop into the recess in the top of the torpedo-slide when drawn back.

Any suitable mechanism may be used for ejecting the spent shell; but I prefer to groove the under side of the slide *g* and to employ a spring, *r*, that is attached to one end within the groove to the under side of the torpedo-slide, and the other end has an ejector-point, *s*, that passes up through a hole in the bottom of the torpedo-cavity. A hanging trigger, *t*, with a finger, *o*, at the upper end, is pivoted close under the torpedo. Upon the top of the base *k* there is a hook, *v*, passing over the spring *r*, at one edge, so that as the torpedo slide and spring are drawn back, the hook will draw down the bent portion of said spring, together with the ejector and the trigger *t*, which will swing back over the end of the spring and hold the same down. The parts will move back and forth in this position as often as desired without the ejector being operated, so long as the torpedo is not fired; but if it is exploded, the pressure of the same upon the finger of the trigger unlatches the spring, so that it is free to project the ejector *s* up under the torpedo-case and throw the same out. It is, however, preferable to hold the spring down until the torpedo-slide begins to draw back, because the spring might fly up and the ejector strike the torpedo while the wheel was pressing on such torpedo, and there would not be the necessary force remaining in the spring to eject the case. To effect this object, I make use of

a second hook, *v'*, upon the base *k*, which hook is above one edge of the spring *r*, and prevents it rising until the slide has been drawn back sufficiently for the end of the spring to draw away from under the hook and allow the spring to act upon the ejector. The further movement of the torpedo-slide causes the spring to be drawn down by the back hook as the spring is moved along below the said hook *v*.

It will be evident that this torpedo-signal might be used alone without the visual signal, if desired.

I claim as my invention—

1. The slide *g*, recessed on its under side and having a recess for the torpedo at the end of its upper surface, in combination with the spring *r*, within the under recess, and attached to the slide *g*, the trigger *t*, with the finger *o* at the upper end, and the ejector *s*, substantially as set forth.

2. The base *k* and slide *g*, in combination with the inclosing-case, the magazine *p*, a spring-ejector, a trigger to hold the spring-ejector out of action until the torpedo has been exploded, and means for moving the slide, and for liberating the ejector, substantially as set forth.

3. The base *k*, the slide *g*, adapted to be moved back and forth, and having a recess for the torpedo, in combination with a spring-ejector beneath the slide, and a trigger to hold such ejector out of action until the torpedo has been exploded, and the hooks *v-v'*, acting upon the spring of the ejector, substantially as set forth.

Signed by me this 28th day of March, A. D. 1883.

T. G. PALMER.
